UNITED STATES PATENT OFFICE.

LUTHER B. THOMAS, OF SHREVEPORT, LOUISIANA, ASSIGNOR OF ONE-TENTH TO J. M. ROBINSON, OF BAYOU LA CHUTE, LOUISIANA.

DISPENSING-BIN.

1,118,381.

Specification of Letters Patent.

Patented Nov. 24, 1914.

Application filed August 13, 1912. Serial No. 714,933.

To all whom it may concern:

Be it known that I, LUTHER B. THOMAS, a citizen of the United States, residing at Shreveport, in the parish of Caddo and State of Louisiana, have invented a new and useful Dispensing-Bin, of which the following is a specification.

This invention relates to dispensing bins, its object being to provide a structure designed to dispense material in measured quantities, the dispensing means being simple in construction, easily adjustable for holding different quantities, and having means combined therewith for preventing material from choking the apparatus and interfering with the proper operation of the parts.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred forms of the invention have been shown.

In said drawings:—Figure 1 is a section through the lower portion of the device, the adjustable slide or measuring device being shown partly in section and partly in elevation. Fig. 2 is a plan view of the segment shown in Fig. 1. Fig. 3 is a section on line A—B Fig. 1.

Referring to the figures by characters of reference 1 designates the main receptacle of the bin, the same being formed with a hopperlike bottom 2, the outlet opening 3 of which discharges into a series of parallel channels 4 preferably of different widths as shown in Fig. 3, and which are separated by partitions 5, these channels being preferably of the same length as the width of the receptacle 1 and being closed at their tops except where the openings 3 are located. Extending downwardly from the bottoms 50 of the channels and adjacent the front ends thereof is an outlet chute or spout 6 having a reduced discharge opening 7 through which material will pass after being deliv-

ered to the spout 6 from any one of the channels 4.

Slidably mounted in each of the channels 4 is a measuring element consisting of side walls 8 connected at their rear ends by a box-like portion or follower 9 having an opening 10 in its back end. A coiled spring 11 is secured at one end to the back wall of each channel and extends loosely through the corresponding opening 10, the other end of the spring being secured to the inner surface of the front end of the follower. This spring 11 serves to retract the follower and the parts connected thereto after a measured quantity of material has been discharged into the spout 6. Each measuring element is extended forwardly beyond the front of the receptacle as indicated at 21 and a lever 22 can be fulcrumed in this extension so as to extend upwardly therefrom. A rod 23 is arranged in the extension and is pivotally connected to the lever 22 and to the adjustable block 24 which can be hollow and fits against the side walls 8. This block also extends throughout the depth of the measuring element. The upper end of the lever has a handle 25 and a spring 26, said dog being adapted to engage a toothed segment 27 mounted on the extension 21. Thus it will be seen that by disengaging the dog from the segment, lever 22 can be swung about its fulcrum so as to move the block 24 toward or from the follower 9. When the dog is in engagement with the segment, however, the handle 25 can be used for shifting the entire measuring element, including its extension 21, relative to the receptacle 1 so as thus to bring the measured quantity of material to the outlet spout 6.

As shown in Fig. 2 a graduated surface 29 may be arranged along one side of the segment, the graduations registering with the teeth of the segment. These graduations can be utilized to designate both the amount of material which will be ejected, and the price to be charged therefor.

Strips 30 may be arranged along the front wall of the opening 3 and along the front upper edge of the followers 9 and can be either metal shearing blades or strips of felt or the like. Metal strips are to be used where large cereals or the like are to be cut.

to prevent choking while felt strips are particularly desirable where small cereals are to be dispensed and it is not necessary to cut any of the material in order to prevent choking or clogging.

What is claimed is:—

A dispensing apparatus of the class described including a receptacle, a channel thereunder, said receptacle discharging into 10 the channel, an outlet spout communicating with the channel, a measuring device slidably mounted in each channel, said device including side walls, a follower connected to the walls at their rear ends, a block slid-

ably mounted between the walls, a handle 15 pivotally connected to and adapted to slide the device, means operated by the handle for adjusting the block toward or from the follower, and means for locking the handle against movement relative to the device.

In testimony that I claim the foregoing as my own, I have hereto affixed my signature in the presence of two witnesses.

LUTHER B. THOMAS.
